(57) **CLAIM**

The ornamental design for eyeglass fittings, as shown and described.

DESCRIPTION

FIG. 1 is a perspective view of a hinge and temple for eyeglasses, showing my new design;

FIG. 2 is an enlarged view of the hinge shown in FIG. 1;
FIG. 3 is a front view of the hinge and temple for eyeglasses of FIG. 1;

FIG. 4 is a right side view thereof, the left side view being a mirror view of it;

FIG. 5 is a top view thereof;

FIG. 6 is a bottom view thereof; and,

FIG. 7 is a rear view thereof.

The material shown in broken lines is for illustrative purposes only and forms no part of the claimed design
